UNITED STATES PATENT OFFICE.

ROBERT M. WHITSON, OF CHICAGO, ILLINOIS.

CLOSURE FOR VESSELS.

No. 911,099.

Specification of Letters Patent.

Patented Feb. 2, 1909.

Application filed January 29, 1906. Serial No. 298,546.

To all whom it may concern:

Be it known that I, ROBERT M. WHITSON, a citizen of the United States of America, and residing at Chicago, in the county of Cook, State of Illinois, have invented a new and useful Closure for Vessels, of which the following is a specification.

My invention relates to certain new and useful improvements in closures for vessels and is designed to furnish means for hermetically sealing vessels, such as jars, bottles, crocks or other containers, which closure is provided with a device for disrupting the seal to open the vessel.

The invention is further designed to furnish means for securely attaching to the cover of the vessel, the disrupting means, so as to facilitate the handling of the parts in assembling the same.

The invention further designs to furnish means to prevent fragments of the disrupted seal from accidentally falling into the contents of the jar.

To such end this invention consists in certain novel features of construction, a description of which will be found in the following specification and the essential features of which will be more definitely set forth in the appended claims.

The invention is clearly illustrated in the drawings furnished herewith in which—

Figure 1 is a plan view of a vessel containing my improved closure. Fig. 2 is a central, vertical section thereof. Fig. 3 is a perspective view of the wire loop that forms the means for disrupting the seal, and Fig. 4 is a perspective view of the cover.

Referring to these drawings 10, represents a vessel here shown as a jar, and 20, represents the cover that is arranged to close the open end thereof. The open end or neck of the jar contains an annular groove 11, below which is a smaller annular groove 12, adapted to receive and hold a thin disk 30, of card-board, paper or the like. The cover 20, is provided with a knob 21, centrally located, and extending above a central depression 22, formed in the upper face of the cover, the upper face of the knob being practically flush with the highest point of the cover and its side tapering down to the cover. A circumferential groove 23, is formed in the periphery of the cover, which groove is adapted to receive and hold a wire loop 41, that forms part of the seal disrupting device 40. As

shown the loop 41 of the disrupting device is in the form of an open ended ring, one end of which is bent upward and inward toward the center of the loop portion, as at 42, where it is bent into the form of a ring 43, which when 60 the disrupting device is applied to the cover, encircles the knob 21. The ring 43 is preferably somewhat less in diameter than the greatest diameter of the knob, so that it may be forced past said part, and into the smaller 65 part of the knob to secure it upon the knob and thereby prevent the ring from accidentally springing up and away from the knob. The advantage of an arrangement of this kind, is perfectly obvious. The end of the 70 disrupting device is in a convenient position to be grasped, and yet is so confined that it is out of the way so as not to interfere with the packing of the jars, and is not liable to become disengaged. The space between the 75 edge of the cover and the neck of the jar is filled with a sealing substance, 50, as for instance paraffin, beeswax, plaster of paris, resin or the like, the loop 41 being completely embedded therein. The undercut 80 groove 11, forms a seat for the sealing substance, and the latter not only hermetically seals the cover to the jar but prevents its removal before the seal is broken.

Immediately below the cover is the disk 85 30, which is sprung into the groove by forcing it past the ridge or annular bead 13, that separates the two grooves 11, 12. The disk 30, forms a sort of supplemental cover for the jar, and is provided for the purpose 90 of preventing any of the fragments, of the broken seal, from falling into the interior of the jar. This is especially desirable, since the vessel may be used to contain food stuffs, or other delicate substances where it 95 is exceedingly important to guard against the entrance of foreign substances.

In operation the jar or other vessel is first filled, after which the disk 30 is sprung into place in the groove 12. The cover 20 with 100 the disrupting device 40 in place upon it, is then placed upon the annular bead or ridge 13, and the sealing substance poured into the annular space between the edge of the cover and the neck of the jar, completely 105 covering the wire loop, filling the groove in the neck and extending slightly over the top of the cover. It will be perfectly obvious that the cover cannot become loosened from any ordinary handling or usage, but 110

- that when the jar is to be opened the seal may be easily broken by simply removing the ring from the knob and drawing upward on the same. The cover 20 can now be removed and any particles of the sealing material that may have fallen upon the disk, may be discharged therefrom. The disk 30 may then be pried away to expose the contents of the jar.
- 10 It should be noticed that the loop 41 is placed in such a position, that when it is pulled out to break the seal, the opening which it makes will permit the cover to be readily withdrawn.
- 15 I claim as new and desire to secure by Letters Patent:
1. The combination with a receptacle having an internal seat and a recess arranged above the seat in the inner wall, of a closure 20 resting on the seat in spaced relation to the inner wall and having its periphery beveled at its top and formed with a recess below the beveled portion.
  2. The combination with a receptacle 25 having an internal seat, of a closure resting on the seat, arranged in spaced relation to the inner wall of the receptacle and having an annular groove, and a seal cutting device arranged in said groove.
  3. The combination with a receptacle 30 having an internal seat, of a closure resting on the seat, arranged in spaced relation to the inner wall of the receptacle and having an annular groove, a seal cutting device arranged in said groove and having an operating portion extending above the closure.
  4. The combination with a receptacle 35 having an internal seat, of a closure resting on the seat in spaced relation to the inner wall and having an annular groove, and a seal cutting device comprising a loop arranged within the groove and having an operating portion projecting above the closure.
  5. A closure for preserving receptacles 40 having a sealing material recess in its periphery, and a seal cutting device carried thereby.
  6. A closure for preserving receptacles 45 having a seal cutting device comprising a loop surrounding the closure and secured to the periphery thereof.
  7. A closure for preserving receptacles 50 having a seal cutting device comprising a loop surrounding the closure and secured to the periphery thereof, and an operating portion projecting from the loop.
  8. In a device of the class described, the combination of a vessel, a cover supported within the neck of the vessel, a sealing material between the neck and cover and a seal disrupting device, carried by, and removably secured upon said cover.
  9. In a device of the class described, the combination of a vessel, a cover adapted to 55 be supported in the open end thereof, a seal- ing material uniting the cover and vessel, an open loop carried by and removably secured upon said cover, said loop being embedded in said sealing material and having an end projecting out through the sealing material 70 within convenient reach of the user.
  10. In a device of the class described, the combination of a vessel, a cover adapted to be supported in the open end thereof, a sealing material uniting the cover and vessel, and a disrupting device including an open loop embedded in the sealing material, the inner end of which is thereby removably secured upon the cover against accidental withdrawal, and the outer end of which projects out through the sealing material within 75 convenient reach of the user.
  11. In a device of the class described, the combination of a vessel, a cover adapted to be supported in the open end thereof and having a peripheral groove, a sealing material uniting the cover and vessel, and a disrupting device including an open loop seated in said peripheral groove, and embedded in the sealing material, the inner end of which is thereby removably secured upon the cover against accidental withdrawal, and the outer end of which projects out through the material within 80 convenient reach of the user.
  12. In a device of the class described, the combination of a vessel, a cover adapted to be supported in the open end thereof and having a knob, a sealing material uniting the cover and vessel, a loop surrounding the cover and embedded in the sealing material, the inner end of which is thereby removably secured upon the cover against accidental withdrawal, and the outer end of which projects out through the material within 85 convenient reach of the user.
  13. In a device of the class described, the combination of a vessel, a cover supported in the open end thereof and having a knob, a sealing material uniting the cover and vessel, a loop surrounding the cover and embedded in the sealing material, an arm upon said loop extending out from said sealing material, and a finger ring upon said arm removably 90 connected to said knob.
  14. In a device of the class described, the combination of a vessel containing an internal peripheral groove, a cover supported in the plane of said groove and having a peripheral groove and a knob, a sealing material uniting the cover and vessel, a loop 95 lying in said groove and embedded in the sealing material, an arm upon said loop extending out from said sealing material, and a finger ring upon said arm removably connected to said knob.
  15. A cover for sealable jars comprising a body portion, having a knob and a peripheral groove, and a wire loop encircling said body and resting in said groove, and having an arm extending up and in toward 100

the center of the body portion and a ring upon said arm removably connected to said knob.

ring removably connecting said loop to the knob.

16. A cover for sealable jars comprising
5 a body portion, having a knob and a per-
ipheral groove, and a wire loop encircling
said body and resting in said groove, and a
